F. HOLST

GAME DEPENDING ON SKILL

Filed Oct. 8, 1925

Inventor:

Friedrich Holst.
Rostock 74
Langenstr. 53

UNITED STATES PATENT OFFICE.

FRIEDRICH HOLST, OF ROSTOCK, GERMANY.

GAME DEPENDING ON SKILL.

Application filed October 8, 1925. Serial No. 61,318.

To all whom it may concern:

Be it known that I, FRIEDRICH HOLST, a citizen of the German Republic, residing at Rostock, in the State of Prussia, in Germany, have invented certain new and useful Improvements in Games Depending on Skill (German application # 413,429 filed September 23, 1924), of which the following is a specification.

10 My invention relates to improvements in games depending on skill in which balls roll down a channelled board upon a horizontal surface, and drop through holes foreseen in this surface, to appear again in one 15 of the numbered compartments. It depends upon the skillfulness of the player to start the balls rolling down the board to obtain higher or lower numbers.

I attain these objects by the arrangement 20 and shape of the boards illustrated in the accompanying drawing, in which—

Fig. 1 is a vertical section of the game on the line 1—1, Fig. 2; and

Fig. 2 is a plan view of the game, and

25 Fig. 3 is a part of the front view of the game.

Similar numerals refer to similar parts throughout the several views. A casing *a* is connected to a channelled board *b* by 30 means of a support *k* a strut *m* and two hooks *o*. Opposite the board *b* a curved deflector *c* in front of the back side of the casing and a depressed horizontal platform

d between said board *b* and plate *e* form the path of the balls used for playing the 35 game. The balls rolling down right or left of said platform *d* enter one of the round holes *f* seen in the horizontal surface *e* through which they drop into the box and rolling over a sloping bottom *g* leave the 40 box through other round openings *h* in front of the box falling into one of the compartments *i* which are numbered as shown in the drawing.

I am aware that prior to my invention 45 games depending on skill have been made in which balls are used to play the game. I therefore do not claim such a combination broadly; but I claim:

The combination in a game depending on 50 skill, of a wooden casing, a channelled board connected to it, a curved deflector at the front of the back side of said casing, a depressed horizontal platform between said curved deflector and the channelled board, 55 a horizontal surface having round holes in this surface a sloping bottom underneath these holes on which balls used for playing the game can drop, round openings in front of the box and numbered compartments to 60 receive said balls, all substantially as set forth.

In testimony whereof I affix my signature.

FRIEDRICH HOLST.
